UNITED STATES PATENT OFFICE.

CHARLES W. DOHM, OF CHICAGO HEIGHTS, ILLINOIS, ASSIGNOR TO PARAFFINE PAINT COMPANY, OF SAN FRANCISCO, CALIFORNIA, A CORPORATION OF CALIFORNIA.

PACKAGE-FORMING MEANS.

1,076,199.

Specification of Letters Patent.

Patented Oct. 21, 1913.

Application filed April 24, 1911. Serial No. 622,956.

To all whom it may concern:

Be it known that I, CHARLES W. DOHM, a citizen of the United States, and a resident of the city of Chicago Heights, county 5 of Cook, and State of Illinois, have invented certain new and useful Improvements in Package-Forming Means, of which the following is a specification.

My invention relates to improvements in 10 package forming means and has for its object the provision of an improved package forming means adapted to form a package for shipping purposes.

The invention consists in the combination 15 and arrangement of parts hereinafter described and claimed.

The invention will be best understood by reference to the accompanying drawings forming a part of this specification and in 20 which,

Figure 1 is a side elevation of the mandrel employed in forming the package, Fig. 2, an end elevation of the mandrel, Fig. 3, an end elevation of the receptacle employed 25 in the device, Fig. 4, a side elevation of the receptacle, Fig. 5, a partial perspective view of the receptacle shown in closed position, Fig. 6, an end view of the receptacle in position on the mandrel for forming the package, Fig. 7, an end view of the receptacle on the mandrel showing the relative positions of the parts at the beginning of forming the package, and Fig. 8, a view similar to Fig. 7, but showing the package in a 30 somewhat later stage of formation.

The package to be formed as illustrated in the drawings comprises a receptacle 1 made of a sheet of fabric such as burlap and rolled into substantially cylindrical form 35 when it is extended with one end secured to the other portion of the sheet by stitching or otherwise as at 2, thus leaving a protruding securing flap 3 as indicated. The same flap 3 is made somewhat narrower 40 than the body of the receptacle so as to leave ends 4 which may be folded inwardly and sewed together by suitable stitching to close the ends of the receptacle.

The mandrel employed for forming the

package is illustrated in Figs. 1 and 2 and 50 comprises a hollow cylindrical body 5 cut away throughout one portion 6 as shown, said portion 6 being of a size to receive the receptacle 1 when filled with the flap 3 protruding as indicated in Fig. 6. 55

The package is intended for shipment of flexible articles such as roofing paper in the form of rolls and the receptacle 1 is intended for the reception of articles such as tacks and washers or other appurtenances 60 such as are sold and shipped with roofing paper. These appurtenances are first placed in receptacle 1 and the ends 4 thereof are closed. Then receptacle 1 is placed in mandrel 5 with the securing flap 3 protruding as 65 indicated in Fig. 6. The end of a sheet of roofing paper 7 is then placed against the package adjacent flap 3 and mandrel 5 is rotated to wind the sheet 7 and flap 3 onto the mandrel, as indicated in Figs. 7 and 8. 70 By this procedure, it will be observed that the securing flap will be inclosed in the coils of the sheet 7 and thus securely hold the receptacle 1 in the roll. The roll is then withdrawn endwise from mandrel 5 and further tied and wrapped as desired for 75 shipment, and will be found to furnish a simple and secure package for the purpose.

While I have illustrated and described the preferred construction for carrying my 80 invention into effect this is capable of variation and modification without departing from the spirit of my invention. I, therefore, do not wish to be limited to the exact details of construction, but desire to avail 85 myself of such variations and modifications as fall within the scope of the appended claims.

Having described my invention what I claim as new and desire to secure by Letters 90 Patent is:

1. As a means for forming a package, a hollow rotatable mandrel adapted to receive a package and supported entirely at one end, said mandrel being cut away at its free 95 end for substantially one-half of its width and for a length substantially equal to the package, substantially as described.

2. As a means for forming a package, a hollow rotatable mandrel adapted to receive a package and supported entirely at one end, said mandrel being cut away at its free end for substantially one-half of its width and for more than one-half the length of the mandrel, substantially as described.

In testimony whereof I have signed my name to this specification in the presence of two subscribing witnesses.

CHARLES W. DOHM.

Witnesses:

W. C. SMITH,
JOSHUA R. H. POTTS.
